UNITED STATES PATENT OFFICE.

ARTHUR H. JELLY, OF CAMBRIDGE, MASSACHUSETTS.

FENDER FOR CARS.

SPECIFICATION forming part of Letters Patent No. 577,859, dated March 2, 1897.

Application filed November 3, 1893. Serial No. 489,966. (No model.)

To all whom it may concern:

Be it known that I, ARTHUR H. JELLY, a citizen of the United States, residing at Cambridge, in the county of Middlesex and State 5 of Massachusetts, have invented new and useful Improvements in Fenders for Cars, of which the following is a specification.

This invention relates particularly to fenders for use on street-cars, especially those 10 propelled by electric or cable power or other means than horse-power, and it belongs to that class of fenders which are held, when in use, ordinarily at a short distance above the track and are arranged to drop at their 15 front edges upon the track in case of necessity, so that an object struck by the fender cannot be run over by it or jammed under it. In this device the fender may drop automatically by the force of the impact against an 20 obstruction on the track or be dropped by the motorman or driver previous to striking the obstacle.

The nature of the invention is fully described below and illustrated in the accompanying drawings, in which—

Figure 1 is a front elevation of a portion of a car equipped with my improved fender, which is shown in the usual position, *i. e.*, raised a little from the track. Fig. 2 is a side 30 elevation of the same. Fig. 3 is a central longitudinal vertical section, a portion of the lifting-chain being represented as broken out. Fig. 4 is a side elevation showing the position of the fender when not in use. Fig. 5 is a plan of a portion of the fender, a small part 35 being represented as broken out. Fig. 6 is a section on line *x*, Fig. 5. Fig. 7 is a perspective view showing the connection and relation of my device to the air-brake mechanism and electrical power, the car-body being removed.

Similar letters and numerals of reference indicate corresponding parts.

A represents the platform of an electric 45 street-car; *A'*, the car-body; *A''*, the dashboard; *A'''*, a seat; *a*, the brake-support, sustained by suitable hangers *a'*; *a''*, the wheels, and *a'''* the steps.

y represents the track-rail.

50 A horizontal bar *B* extends longitudinally and centrally rearward from the brake-support *a*, and its rear end is sustained by a

suitable hanger *B'*, secured to the under side of the car-body.

C is a cross-piece which slides on the bar 55 and is provided with a rearward extension *C'*. A plate *C''* is secured to the under side of the cross-piece beneath the bar *B*. The bar *B* is provided near its forward end with a vertical hole which, when the cross-piece *C* is slid forward as far as is possible, becomes coincident with similar holes in the cross-piece *C* and plate *C''*, so that a bolt *b* may be dropped into said holes and lock the cross-piece in a 60 forward position.

D is a horizontal and transversely-arranged spring whose central portion bears against the rear side of the extension *C'* on the sliding bar *C*, while its outer ends, which bend rearward, are engaged by links *D'*, which extend through suitable openings in the spring and are adjustable therein by means of nuts *D''*. The forward ends of these links *D'* are pivotally attached at *d* to the lower portions of the rear ends of the triangular arms *E*. 70 These arms are pivotally secured at *d'*, near the upper portions of their rear ends, to the opposite ends of the sliding cross-bar *C*.

The arrangement of the spring *D*, links *D'*, and triangular arms *E* is not new in this invention. The effect is that the spring *D*, 80 whose central portion bears against the rear side of the extension *C'*, pulls on the links *D'* and draws the front ends of the arms normally down.

The arms *E* are connected near their rear ends by a cross-bar *E'*, which, with said arms, constitutes a supporting-frame for sustaining the bottom part or basket or fender proper, *F*. This part *F* constitutes a tilting fender, 90 and consists of the frame, which is lettered *F*, the network or grating *F'*, and the roller *F''*, sustained in the front portion of the frame. The bottom or fender proper, *F*, is hung pivotally at *e* from the outer ends of the arms *E*, 95 and as the points at which it is hung are at some distance from the rear edge of its frame it tilts in the frame instead of swinging, as does a fender which is hinged at its rear edge to its support. The bar *E'* is horizontally perforated at *f* (see Figs. 5 and 6) and bolts *g* are let into the perforations, the heads of said bolts being held in the perforations by means of shoulders *f'*. These bolts extend against the 100

rear edge of the tilting fender F and are held normally in such position by springs g', confined in the holes f by screws g''. Thus the friction of the bolts holds the tilting fender 5 normally in line with the frame E E'. The fender is prevented from tilting down at its rear edge (or up at its front edge) by stops l, Fig. 5, which consist of extensions of the rear bar of the frame, such extensions overlapping 10 portions of the arms E.

The fender and frame are sustained in the raised position shown in the drawings by means of the following mechanism: The bunter H is hollow and open at top and bottom. 15 Pivoted within it at H' is a latch or trip I, the upper end of which extends up slightly above the bunter and the lower end slightly below it. The lower arm of the catch I is held normally forward by a spring I', which lies in an 20 opening in the front edge of the platform A and extends against said catch. A chain or cord J extends from the cross-bar E' and catches over the upper end of the catch I by means of a suitable lock or ring. Pivoted at 25 K' to suitable ears or bars O beneath the car-platform is the trip-lever K, whose front end rests normally against the rear surface of the lower portion of the catch, being held in such 30 position by the spring K'', secured to the under side of the car. A chain or cord L is hooked into a ring K''' on said trip-lever, and passing through the notch E'', Fig. 5, in the rear edge of the bar E' has its lower end caught upon a ring L' on the under side of the tilting fender F. A bolt or plunger N lies in a vertical hole in the platform with its head convenient to the foot of the motorman, while its lower end rests on the front portion of the trip-lever K, whose front end is preferably 35 provided with an antifriction-roller l'. A chain or cord P has its lower end secured to the lower edge of the tilting fender F, while its upper end catches a hook P', secured to the dashboard within reach of the motorman. 40

45 When the fender is in position for service, *i. e.*, the position shown in Figs. 1, 2, and 3, the forward end of the tilting portion is raised a little from the track. In case the motorman sees danger ahead he pushes down the bolt 50 N, and hence the forward end of the trip-lever K, which releases the lower end of the catch or trip I. The upper end of the catch flies forward into the position shown in broken lines in Fig. 3, and the chain J, which has 55 been holding up the fender-frame by means of the bar E', allows the fender-frame to drop, it being forced downward by the action of the spring D through the links D' on the arms E until the roller F'' touches and is held on the 60 track, as shown in broken lines in Fig. 3. This roller bears constantly upon the track, even should the car rock considerably, as the hinging of the arms E allows the spring D to continue its pressure. Any object on the 65 track, therefore, would be taken up by the fender and could not work under it. After the danger is over the chain P may be used

to lift the fender-frame into its former position, when the catch I will resume its original position by means of the spring I', and the trip-lever K will do the same by means of the spring K''. When the fender is tipped down, as above mentioned, the relieved trip-lever K allows the chain L to accompany the chain J down sufficiently to allow the fender free 75 movement.

In case an object on the track should be struck and the motorman fail to trip the fender the blow of the front edge of the tilting bottom F against the object tilts down the 80 front edge upon the track, overcoming the friction of the bolts g, which project against the rear edge, and then by the lift or rise of the rear edge of the tilting frame F causes the chain L (which passes through the notch E'' to the under side of the said tilting frame) to pull down the trip-lever K and release the catch; but even if the blow should fail to release the catch the tilting fender-bottom tilts down and prevents an object from getting under the fender. A pull on the chain P tilts back the part F as well as lifts the fender-frame.

When the fender is to be stowed away, the bolt N is pressed down, releasing the trip. 95 Then the chain J is removed from the catch I by moving the upper end of said catch forward, the chain L removed by lowering the trip-lever K, the two chains dropped upon the fender, the bolt b removed, and the fender and frame lifted and slid back on the bar B, the front end being finally caught and held up by the knob S, over which the ring P'' is caught, said ring being the connection between the lower end of the chain and the front 105 end of the fender, all as shown in Fig. 4. The ring P'' in the chain P is then caught on the hook P'. The chain P may be unhooked at either end and left either on the fender or suspended from the hook P', as desired. The 110 bolts N and b may either or both be removed and used at the other end of the car.

It is deemed desirable that the impact of the fender against an object on the track should not only cause the fender to drop or 115 tilt down, but cause the brake to be applied and shut off the power as well. These three results—viz., dropping the front edge of the fender, shutting off the power, and setting the brake—are effected substantially simultaneously by the impact of the fender against an obstruction by means of the following mechanism, especial reference being directed to Fig. 7: The rear end of the lever K is bent downward, as shown, so as to engage with a 120 ratchet-wheel 2, fast on a shaft 1, having its bearings in hollow circular boxes or drums 3, secured to the under side of the car-body by brackets 4. The ratchet-wheel is held against the lever or pawl K by means of springs 5 125 within the boxes 3, one end of a spring being secured to a box 3 and the other end to the shaft 1. A cord 6 has its ends secured to the shaft 1 and is wound oppositely thereon, its

central portion passing over suitably-hung pulleys 7 and around a horizontal wheel 8, fast on a spindle 9, extending from the valve 10 in the pipe 11. One end of this pipe 11 is connected, by means of a branch 12, with the pipes 13, 14, and 15, leading to the auxiliary reservoir 16, connected with the pump. The other end is connected, by means of the branch 17, with the pipe 18, leading, by means of the branch 19, to the "jam" or brake-cylinder 20, which connects with the brake-lever 21 by means of the piston 22. The pipe 13 is connected, by means of the pipes 23 and 24, with the valve 25, 26 being the valve-handle, and the pipe 18 is connected, by means of the pipe 27, with the valve. The main reservoir 28 is connected, by means of the pipes 29, 30, 31, and 32, with the valve 25.

33 is the exhaust.

20 The arrangement comprised in parts numbered 11 to 33, inclusive, constitutes an ordinary air-brake mechanism and needs no further description.

Now when the impact of the tilting fender causes the front end of the lever K to be pulled down, as above explained, the rear end necessarily simultaneously releases the ratchet-wheel 2, and the shaft rotating causes the cord 6 to give a greater rotation to the wheel 8, at the end of which it stops by reason of the cord being secured thereto at 34. The wheel 8 operates the valve 10, and the air-brake is set in the well-known manner.

Attached at its ends to and wound oppositely upon the shaft 1 is a cord 35, which passes over suitably-supported pulleys 36 and around pulleys 37, as shown. This cord is connected at the point shown with an ordinary electrical switch 38, by means of which 40 the electrical current in the wires 39 may be cut out. Thus it will be seen that the dropping of the front edge of the fender, the setting of the brake, and shutting off the current all occur simultaneously and consequent 45 on the impact or blow of the fender on an obstruction on the track.

The shaft may be returned to its original position, and hence the wheel 8 and switch 38, by a pull on the part of the driver or motor-man on the cord 40, which is wound around and secured to a pulley 41, fast on the shaft 1, and extends over the pulley 42 and may be hung by means of a ring 43 on the hook 44 on the dashboard, after which the brake is released in the usual manner.

In practice it is desirable to provide some adjusting device for the chains J and L, whereby either may be adjusted as to length with relation to the other.

60 Of course it will be understood that the shape and especially the width of my tilting fender-bottom may be varied as desired, so long as its tilting quality is retained.

Having thus fully described my invention, 65 what I claim, and desire to secure by Letters Patent, is—

1. A tilting fender sustained in a fender-

frame between the front and rear edges of the fender, said tilting fender being adapted to have its front edge tilted down from its normal raised position by the substantially horizontal impact of said front edge against an object on the track, substantially as set forth. 70

2. A fender pivotally sustained at a point between its front and rear edges by a vertically-movable fender-frame, said fender being thereby adapted to tilt down at its front end from a normally-raised operative position toward the road-bed, substantially as set forth. 75

3. A tilting fender sustained pivotally in a fender-frame at a point between the front and rear edges of the frame or body of the fender, and a spring arranged and adapted to hold the said tilting fender with sufficient strength or firmness to resist a tendency to have its front edge raised by the force of its substantially horizontal impact against an object on the track, but to allow the said tilting fender to yield to the substantially vertical blow on its under side produced by the rocking or oscillation of the car, substantially as set forth. 80 85 90

4. In a fender, in combination, a bar or frame sliding longitudinally under the car, a fender-frame hinged to said sliding frame or bar, and a fender-bottom pivotally secured to 95 and tilting on said fender-frame, substantially as described.

5. A tilting fender sustained pivotally at a point between the front and rear edges of its body portion, and adapted to be slid substantially horizontally under the car, substantially as described. 100

6. In combination, a tilting fender sustained pivotally at a point between the front and rear edges of its body portion, and a 105 longitudinal supporting-bar sustained beneath the car, whereby the fender is adapted to be slid substantially horizontally under the car, substantially as set forth.

7. The combination of the frame comprising the bar E' and arms E, said bar being provided with the horizontal holes f, springs g', bolts g and screws g'', and the fender-bottom tilting in said frame and held normally in line therewith by said bolts pressing against 115 its rear edge, substantially as described. 110

8. A fender-frame and fender-bottom tilting in said frame, said fender-bottom being held normally in line with said frame by a friction mechanism between the frame and bottom, substantially as set forth. 120

9. In combination, the car-body provided with the trip-lever K pivoted to said body, the bunter provided with the trip I bearing normally against the front end of said trip-lever, 125 the spring I', the hinged fender-frame and the chain J connecting said frame and trip, said raised trip-lever holding the lower end of the trip normally forward, substantially as described. 130

10. In combination, the car-body provided with the trip-lever K pivoted to said body, the bunter provided with the trip I bearing normally against the front end of said trip-lever,

the hinged fender-frame, and the chain J connecting said frame and trip, said trip-lever holding the lower end of the trip normally forward, substantially as described.

5 11. In combination, the car-body provided with the trip-lever K, the bunter provided with the trip I, the spring I', the hinged fender-frame E E', and the chain J connecting said frame and trip, the tilting fender-bottom

10 F, and the chain L connecting said bottom and trip-lever, substantially as described.

12. In combination, the car-body provided with the trip-lever K, the bunter provided with the trip I, the spring I', the hinged fender-frame E E', the chain J connecting said frame and trip, the tilting fender-bottom F,

15 the chain L connecting said bottom and trip-lever, and the chain P connecting the front portion of said fender-bottom with the car in

20 a place accessible to the motorman, substantially as set forth.

13. The combination of the fender-frame E E' and the tilting fender F, the latter being provided with stops l whereby the front edge

25 is prevented from tilting up, substantially as described.

14. In combination, a vertically-hinged fender-frame, a fender-bottom sustained by said frame and pivotally secured thereto, and a

30 stop whereby the front edge of the fender-bottom is prevented from being tipped up by impact independently of the frame, substantially as set forth.

15. A vertically-hinged fender-frame provided with a life-saving scoop or fender-bottom adapted to be tripped or dropped by the direct impact of an object on the track against the front edge as distinguished from an attachment thereto, substantially as set forth.

35 40 16. A vertically-hinged fender-frame provided with a life-saving scoop or fender-bottom adapted to be tripped or dropped by its

direct impact against an object on the track, and held down in continuous contact with the track by a spring, substantially as described.

17. In combination, an air-brake mechanism, an electrical switch for turning on and cutting out an electric current, the shaft 1 supported by the car-body and provided with

50 the spring 5 and ratchet-wheel 2, the lever K engaging with said ratchet-wheel and operated by the dropping of the car-fender, the wheel 8 actuating the valve 10 and connected with the shaft by the cord 6 secured at its

55 ends to and wound reversely on said shaft, the cord 35 secured at its ends to and wound reversely on the shaft and connecting with the electrical switch, and the cord 40 wound on the shaft and leading to a point within

60 reach of the driver, substantially as set forth.

18. In combination, a vertically-hinged fender-frame provided with a life-saving fender or guard, a slideway suitably attached to a car, a slide supported by and moving longitudinally with relation to said slideway and

65 connecting said slideway and fender whereby the fender may be brought forward from a retracted inoperative position beneath the car into a substantially non-vertical position

70 for operative use, suitable means of support whereby the fender may be maintained with its front end normally raised from the road-bed or track when in said forward operative position, and mechanism within control of

75 the motorman or driver whereby the said front end may be instantly brought down in case of emergency from said normally-raised operative position toward the road-bed or track, substantially as set forth.

ARTHUR H. JELLY.
